UNITED STATES PATENT OFFICE

170,481

FLASHLIGHT

Martin Schnur, Newark, N. J., assignor to Bright Star Battery Company, Clifton, N. J., a corporation of New Jersey

Application November 19, 1952, Serial No. 22,366

Term of patent 14 years

(Cl. D48—24)

To all whom it may concern:

Be it known, that I, Martin Schnur, a citizen of the United States of America, residing at Newark in the county of Essex and State of New Jersey, have invented a new, original, and ornamental Design for a Flashlight, of which the following is a specification; reference being had to the accompanying drawing forming part thereof.

Fig. 1 is a front perspective view of a flashlight showing my new design;

Fig. 2 is a side elevational view thereof, the opposite side being the same; and

Fig. 3 is a rear elevational view.

I claim:

The ornamental design for a flashlight, as shown and described.

MARTIN SCHNUR.
